UNITED STATES PATENT OFFICE.

FREDERICK W. H. WEISHAUP, OF WASHINGTON, DISTRICT OF COLUMBIA.

BED SPRING AND FRAME.

966,723.

Specification of Letters Patent. Patented Aug. 9, 1910.

Application filed March 29, 1909. Serial No. 486,546.

To all whom it may concern:

Be it known that I, FREDERICK W. H. WEISHAUP, a citizen of the United States, residing in the city of Washington, in the 5 District of Columbia, have invented certain new and useful Improvements in Bed Springs and Frames; and I do hereby declare the following to be a full, clear, and exact description of the invention, such as 10 will enable others skilled in the art to which it appertains to make and use the same.

This invention relates to beds and has special reference to a frame for bed springs and a spring therefor.

15 One object of the invention is to improve the general construction of bed springs and frames.

Another object of the invention is to provide a means whereby different portions of a 20 bed spring may be separately tensioned so that sagging of one part is prevented.

A still further object of the invention is to provide a novel form of bed spring constructed in independent sections arranged to 25 support each other at their proximate edges.

With the above and other objects in view the invention consists in general of a bed frame carrying a plurality of spring sections and means for independently adjusting each of said sections.

The invention further consists in certain novel details of construction, and combinations of parts hereinafter fully described, illustrated in the accompanying drawings, 35 and specifically set forth in the claims.

In the accompanying drawings, like characters of reference indicate like parts in the several views, and—

Figure 1 is a top plan view of a bed frame 40 and spring constructed in accordance with this invention. Fig. 2 is a section on the line 2—2 of Fig. 1. Fig. 3 is a section on the line 3—3 of Fig. 1. Fig. 4 is a section on the line 4—4 of Fig. 2. Fig. 5 is a section on the line 5—5 of Fig. 2. Fig. 6 is a section on the line 6—6 of Fig. 1. Fig. 7 is a view of the lever used with this invention. Fig. 8 is a longitudinal view of a modified form of stationary or fixed end. Fig. 9 is a cross 45 section on the line 9—9 of Fig. 8.

This bed spring and frame consists in

general of a substantially rectangular frame comprising end bars 10 adjacent each end of which are side rails 11 firmly secured to the end bars by means of bolts 12. The end bars 55 10 are preferably made of angle iron while the side rails 11 are of pipe or other tubing. In order to prevent the access of vermin to the side rails 11 these side rails are provided with a closure at each end in the form of a 60 substantially circular plate 13 provided with projections 14 bent at right angles to the plate 13 and held to the each end of the side rails 11 by means of the bolt 12 which passes through a suitable perforation in the 65 projection 14.

Securely riveted to the extreme ends of the end rails 10 are brackets 15 each provided in its upper portion with a circular socket 16 adapted to form a bearing. Between the 70 bracket 15 at one end of the frame extends a pipe section 17, integral throughout its length and having its ends supported in the respective sockets 16. This pipe section 17 is held from rotating in the sockets by means 75 of rivets 18. This pipe section 17 is also provided on its upper side with a plurality of openings 19 wherein are held the ends of wire hooks 20 the other ends of which are engaged in openings 21 formed in a clamp 80 member 22 between the edges of which are engaged a series of woven wire spring sections 23 the proximate edges of which are so interwoven that each of these sections may have independent movement with reference 85 to the remainder and in regard to its length. Supported in the brackets 15 at the other end of the frame are pipe sections 24 each of which is freely revoluble in the journal formed by the socket 16. Each of the sections 24 is provided in the end opposite the bearings with a pipe section 25 of the same diameter as the interior of the pipe and which is securely held within the pipe by means of a rivet 26. Intermediate the sections 24 are other sections 27 of similar character and these sections are fitted over the ends of the pipes 25 to be freely revoluble thereon. These sections are also joined by means of a pipe section 28 secured to one of 100 the sections by a rivet 29. It will be observed that this construction permits the

free revolution of any one of the sections without reference to the adjacent section and that the short sections provide a means whereby the sections have their adjacent ends mutually supported so that the entire length of pipe from bracket to bracket forms a stiff sectional roller. Each of these sections 24 and 27 is provided with a series of openings 30 in each of which is held one end 5 of each of a pair of wire hooks 31 the opposite ends of which are held in suitable perforations 32 formed in sectional clamping members 33, there being one of these clamps to each of the sections 23 of the bed 10 spring.

Each of the sections 24 and 27 is provided, preferably intermediate its ends with a circumferential series of staggered openings 34 adapted to receive one end of a locking bar 20 35 the opposite end of which is bent to engage beneath the edge of the member 10. Covering the openings 34 is a sleeve 36 so cut away on its edge as to permit the introduction of the hook 35 in one of said openings while at the same time the remainder of the openings are covered to prevent access of vermin to the interior of the roller. In order to rotate the sections there is provided a suitable lever having an end adapted 25 30 to enter the perforations 34 and this lever is shown in Fig. 7 wherein the handle portion is indicated at 37 and the end referred to at 38.

In order to tension any certain portion of 35 the bed, so that inequalities of the surface may be overcome or so that provision may be made for persons of more than usual weight, the end 38 of the lever is inserted in one of the perforations 34 and passed out 40 through the opposing perforation. The lever is then forced in the proper direction and that section of the roller rotated until the desired tension has been reached, the wires 31 bending around the roller as this 45 operation is carried out. The first movement of the roller loosens the hook 35 which is removed until the proper tension has been brought on the spring section 23. When this is accomplished the hook 35 is replaced 50 in the proper opening and the lever 37 removed. By this means any one of the sections may be tensioned to any required degree without interfering with the remainder of the sections, the arrangement thus constituting a means for separately tensioning 55 each of said sections.

There has thus been provided a simple and efficient device of the character described and for the purpose specified.

60 In the modified form shown in Figs. 8 and 9 the brackets 16 at the fixed end are replaced by means of brackets 39. Attached to the upper side of these brackets 39 is a

plate 40 secured on which is a ribbon or bar 41. Between the plate 40 and the bar 41 are 65 clamped the fixed ends of the spring sections 23. It will be obvious that in this modification the pipe section 17, wire hooks 20 and clamp member 22 are dispensed with.

It will be noted from the construction of 70 this device that by removing or adding to the number of sections 27 the tensioning device may be made to accommodate any desired width of bed spring from that used on a single bed to a full double bed.

Having thus described the invention, what is claimed as new and desired to be secured by Letters Patent, is:—

1. In a device of the kind described, a tensioning mechanism comprising a plurality 80 of revoluble roller sections having their adjacent ends mutually supported for independent revolution, each of said sections being provided with a plurality of circumferential openings adapted to receive the end 85 of a lever, a stationary frame element, and hooks each adapted to engage one of the openings of each series and the stationary frame element.

2. In a device of the kind described, a 90 rigid bed spring frame, a plurality of spring sections each having one end fixedly secured to said bed spring frame, and means for separately tensioning each of said sections attached to the free ends thereof and supported at the opposite end of said frame, said means comprising a plurality of revoluble roller sections having their adjacent ends mutually supported for independent revolution, means to independently revolve 100 each of said sections and other means to hold said rollers in position when revolved.

3. In a device of the kind described, a rigid bed spring frame, a plurality of spring sections each having one end fixedly secured 105 to said bed spring frame, and means for separately tensioning each of said sections attached to the free ends thereof and supported at the opposite end of said frame, said means comprising a plurality of revoluble roller sections having their adjacent ends mutually supported for independent revolution, each of said sections being provided with a plurality of circumferential openings adapted to receive the end of a lever, 115 and hooks adapted to engage one of the openings of each section and the rigid bed spring frame.

4. In a device of the kind described, a rigid bed spring frame, a plurality of spring 120 sections having their adjacent edges interwoven and slidably relative to each other, each of said sections having one end fixedly secured to said bed spring frame, and means for separately tensioning each of said sections attached to the free ends thereof and

supported at the opposite end of said frame, | said means comprising a plurality of revolu-
ble roller sections having their adjacent ends | mutually supported for independent revolu-
tion, each of said sections being provided | with a plurality of circumferential openings | adapted to receive the end of a lever, and | hooks adapted to engage one of the openings |

of each section and the rigid bed spring | frame. | 10

In testimony whereof, I affix my signa-
ture, in presence of two witnesses.

FREDERICK W. H. WEISHAUPt.
